CLAIM

The ornamental design for an identification tag, as shown and described.

DESCRIPTION

FIG. 1 is a perspective view of an identification tag showing my new design;

FIG. 2 is a front elevational view thereof, the rear elevational view being substantially a mirror image thereof;

FIG. 3 is a right side elevational view thereof, the left side elevational view being substantially a mirror image thereof;

FIG. 4 is a top plan view thereof;

FIG. 5 is a bottom plan view thereof;

FIG. 6 is a front elevational view of a second embodiment of the identification tag shown in FIG. 1; and

FIG. 7 is a right side elevational view thereof, the left side elevational view being substantially a mirror image thereof.

The top plan view and bottom plan view, FIGS. 4 and 5 respectively, are substantially identical in the alternate embodiment.
